Toshiyuki Tokoi(57) **CLAIM**

The ornamental design for an ionizer, as shown and described.

DESCRIPTION

FIG. 1 shows a front view of an ionizer showing our new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof;

FIG. 7 shows a bottom, front and left side perspective view thereof; and,

FIG. 8 shows a top, rear and right side perspective view thereof.

The portions of the design shown in broken lines in FIGS. 1 to 8 are for the purpose of illustrating the environment only and form no part of the claimed design.

The present article is comprised of a body portion and a discharge needle unit.

The body portion includes a fan at a ventilation hole. The discharge needle unit includes a metal grille and a discharge needle. The discharge needle unit is formed in a plate shape. The discharge needle unit is detachably mounted on the body portion. By blowing an air containing an ion generated at the discharge needle, electricity charged on a work can be eliminated.
